UNITED STATES PATENT OFFICE

2,297,750

FILAMENT MOUNTING MACHINE

John Flaws, Jr., East Cleveland, Ohio, assignor to
General Electric Company, a corporation of
New York

Application July 24, 1940, Serial No. 347,242

27 Claims. (Cl. 176—4)

My invention relates to the manufacture of filament mounts for electric incandescent lamps and similar devices, and more particularly to automatic apparatus for reshaping and repositioning the lead wires of such devices and mounting filaments thereon. Still more particularly, my invention relates to apparatus for automatically mounting a filament accurately in predetermined relation to a reflector constituting part of the lamp or similar device, the apparatus also preferably including means for testing the reflector to determine its light redirecting properties and the optimum location for said filament.

Heretofore, some difficulty had been experienced in maintaining accuracy in the manufacture of electric lamps in general, and lamps having an integral reflector in particular. Accuracy in manufacture is, of course, very desirable since the proper control of the light emitted by such lamps depends on the accurate location of the light source. The inaccuracies encountered heretofore were due both to the mount making operation and to various inaccuracies in the vitreous portions of the lamps which are the basic means of supporting the filament. To nullify these inaccuracies special base constructions or adjustable mountings had to be used to compensate for the variations in the lamp.

One object of my invention is to provide mount-making apparatus which operates with positiveness and accuracy to eliminate possible errors which might be caused by looseness in the mounting apparatus due to the working freedom or wearing of portions of said apparatus, and by distortion of portions of said apparatus or the lamp parts due to operating strains. To eliminate these errors and accomplish this object, the mount-making apparatus comprising my invention is operated hydraulically and is divided into self-contained devices separated from the main body of the apparatus. Such apparatus is also constructed and arranged so that no pressure is exerted on the lead wires or other lamp parts which could cause displacement thereof.

Another object of my invention is to provide apparatus for accurately locating the lamp parts introduced into the mounting apparatus with respect to various devices thereon so that the mount is constructed thereon at the location desired. Some variations are allowable in the lamp parts on which the mount is developed providing said parts are located in the mounting apparatus with respect to the same reference portions of said parts which are used to establish the position of the lamp and light source in 55

illuminating apparatus in which the lamp is subsequently to be used. The parts of the lamp from which the reference points are taken may be the vitreous body supporting the leads and 5 may be the cup or reflector section of the bulb of the particular lamp disclosed in the United States Patent No. 2,148,314 to D. K. Wright. The desired means of causing these parts to be positioned correctly with respect to the various 10 mount-making devices is to have all of such devices operate exactly at one common elevation or correspondingly established position and to locate the lamp parts in a manner which permits them to be readily advanced to said elevation 15 or position.

A carrier is preferably provided to advance the lamp parts into operative relation to the different mount-making devices which are located at a plurality of stations, and the rigidity of the 20 carrier is depended upon to maintain the position of the lamp parts once they are properly positioned thereon. When the vitreous body supporting the leads to which the filament is to be attached is in the form of the reflector section 25 or cup of the bulb, as disclosed in the Wright patent hereinbefore referred to, the method and apparatus disclosed by E. J. Westerlund in his application Serial No. 291,722, filed August 24, 1939, is preferably used to ascertain the focus 30 of the reflector, and said reflector section or cup is positioned on the carrier with reference thereto.

Another object of my invention is to provide 35 mount-making apparatus for bending and positioning the leads supported by the vitreous body to a definite location regardless of any variations in the original position thereof. Such apparatus assists in eliminating errors in mounting the filament and also eliminates any damage to the 40 vitreous body holding the leads.

Another object of my invention is to provide 45 apparatus for reshaping the ends of the leads and attaching the ends of the filament thereto to provide a strong mechanical and electrical connection therebetween. Another object of my invention is to provide apparatus for definitely controlling the position of the filament in the mounting apparatus at all times and for bringing said filament into the correct mounting relation 50 to the leads and the vitreous body.

Further objects, features and advantages of my invention will appear from the following detailed description of a species thereof which is particularly adapted to form the filament mount for the reflector type lamp disclosed in the

Wright Patent No. 2,148,314 hereinbefore referred to. In that instance, the leads are arranged in a definite manner at the center of a preformed vitreous cup having a reflecting coating on the inner surface thereof, and the embodiment of my invention herein specifically illustrated automatically reshapes the ends of the leads and mounts two filaments thereon at specific locations with respect to the reflector formed by the said coating.

In the drawings, Fig. 1 is a plan view of a machine embodying mount-making apparatus comprising my invention which, as shown, is arranged about the work stations A to H and J to K, inclusive; Fig. 2 is a perspective view on a large scale of the filament mount manufactured by the machine disclosed; Fig. 3 is a perspective view of the under side of the preformed vitreous cup on which the filament mount is developed; Fig. 4 is a vertical section through station B and the half of said machine along line 4-4 in Fig. 1 showing the focus finding device and cup positioning apparatus thereat; Fig. 5 is a perspective view of one of the heads of the machine from which portions thereof have been broken; Fig. 6 is a front elevation of the lead-positioning means and the focus-finding device at station B; Fig. 7 is a perspective view of one portion of the lead-positioning means on a larger scale and in operative relation to the leads; Fig. 8 is a perspective view of photo-cells employed in the focus-finding device and a portion of the supporting means therefor on a larger scale; Fig. 9 is a piping and wiring diagram of the hydraulic and electrical operating means respectively for the entire machine, the cams on shaft 67 being shown widely spaced for clearance although they are actually close together as shown in Fig. 4; Fig. 10 is a perspective view of one of the locking devices at stations C and D; Fig. 11 is a perspective view of the lead-prelocating and bending device located at station C; Figs. 12 and 13 are side and bottom views respectively of the lower portion of said device on a larger scale; Fig. 14 is a perspective view of the bending device located at station D; Figs. 15 and 16 are side and bottom views respectively of the lower portion of said device with portions broken away to show underlying parts; Figs. 17 and 18 are perspective and side views of the lower portion of the lead-trimming device located at station E; Fig. 18' is a rear perspective view of a slide portion of the trimming device; Fig. 19 is a side elevation of a device located at station F for grooving the ends of the leads 37 and 38 to form pockets therein for receiving the ends of a filament; Fig. 20 is similar side elevation of the lower end of said device with portions broken therefrom to show squeezing jaws and associated means; Fig. 21 is a plan view looking upward and on a larger scale of the lower end of said device; Fig. 21' is a perspective view of lead wire positioning means; Fig. 22 is a perspective view of a control arm of a swaging or hammering means and a feeler arm for the cup at station G; Fig. 23 is a plan view looking upward of a portion of the grooving device at station G; Fig. 24 is a perspective view of a filament feeding turret, a filament transferring device and a groove clamping device located adjacent station H; Fig. 25 is a perspective view, on an enlarged scale, of a portion of the feeding turret including one of the filament holders and a filament spaced therefrom; Fig. 26 is a side elevation of supporting and indexing means for the filament feeding turret; Fig. 27 is a perspective

view of the transfer device with numerous sections broken therefrom to show all portions of the device more clearly; Figs. 28 and 29 are enlarged perspective and side views of jaws of the

5 transfer device; Fig. 30 is a section through the transfer jaws along the line 30-30 of Fig. 28 and Fig. 29 in the direction indicated; Figs. 31 and 32 are side elevations at 90° to each other of the lower end of the clamping device at station 10 H; and Fig. 33 is a plan view looking upward of said device on a larger scale; Fig. 34 is a similar plan view on a still larger scale of clamping dies of the corresponding clamping device at station J; and Fig. 34' is a perspective view of control 15 mechanism for the clamping device.

The first act necessary to the operation of the mount making machine shown in the drawings is the insertion of a vitreous cup or body 35 supporting a plurality of leads 36, 37, 38 and 39 (Figs. 20 1 and 2) into the head 40 of said machine located at station A. The vitreous cup 35 shown is in the form of the reflector section of an incandescent lamp of the type disclosed in the Wright Patent No. 2,148,314 previously referred to, in that it is provided with a reflective coating 41, preferably a deposit of aluminum, on the inner surface and supports the leads 36 to 39, inclusive, on posts 42 extending through openings therein and, attached to metal thimbles 43 sealed thereto. The metal thimbles 43 are arranged about the vitreous exhaust tube 44 which is sealed to the center of the vitreous cup 35 as shown in Fig. 3 and bear a general relationship to three sets of two low lugs or protuberances 45 and definite angular relationship to a single larger lug or protuberance 46 between the low lugs 45 of each set. The lugs 45 and 46 are located on the under-side of the rim 47 of said vitreous cup 35 and are integral therewith.

40 The motion of inserting the cup 35 into the head 40 of the machine consists in moving said cup 35 down under the positioning means 48 and over onto the stationary holder 49 shown in Figs. 4 and 5. At this time, the movable holder 50 is much lower than shown in the drawings and the cup 35 is lowered until the rim 47 thereof rests directly on the stationary holder 49. The cup 35 must also be orientated at this time until the lead 36 is at the operator's left, lead 37 is at the 45 opposite side of said cup 35 from said operator and the leads 38 and 39, which extend from a common post 42, are at said operator's right. When correctly orientated, one of the larger lugs 46 falls into the opening formed by the lips 51 50 on the plate 52 on the outer surface of the stationary holder 49 and prevents any further rotative motion thereof. Should the cup 35 be off center when inserted the more angular sides thereof will engage the edge of the stationary holder 49 and said cup 35 will be shifted to the correct position. The stationary holder 49 is mounted on two correspondingly positioned studs 53 at opposite sides thereof which extend upward from the circular plate 54 which in turn 55 provides vertical slide ways for the spindle 55 supporting the movable holder 50. The circular plate 54, in turn, is mounted on the turret 56 which provides an extremely rigid support for the parts of the head 40 in that it is mounted on the large hollow center post 57 of the frame (not shown) of the machine by means of the ball bearings 58 and 59. The frame is a large solid unit under the turret 56 and provides the support for the entire machine, and the holder 50 and spindle 55, in particular, through indirect sup-

port of the track 60 which is engaged by the roller 61 on the lower end of said spindle 55.

Lateral stability of the head 40 and, accordingly, of the turret 56, depends upon the indexing means engaging the turret 56 and advancing the heads 40 into operative relation to the various work devices at the different stations about said turret 56. Each head 40 is represented by a single tapered roller 62, like those shown in Fig. 4, which is mounted on a pin 63 extending from the ring 64 attached to said turret 56 and, between indexing movements, is held at a very definite position by a portion of the cam 65 located between two of such rollers 62 (Fig. 9). During rest periods of the head 40, a uniformly shaped portion 66 of the cam 65, which is mounted on the main drive shaft 67, passes between the rollers 62 as said cam 65 rotates but, during indexing periods, the curved channel 68 in said cam 65 is moved over one of the rollers 62 and advances it into the prior location of the other roller. All movement of the rollers 62 and, therefore, of the heads 40, is directly under the control of the cam 65 and no misplacement of the head 40 can exist at any time.

The stationary holder 49 supports the cup 35 at a temporary position from which it is transferred during the movement of the head 40 from station A to B by an upward movement of the movable holder 50. In moving from station A to B, the roller 61 on the end of the spindle 55 is carried up an inclined portion (not shown) of the track 60 which lifts said spindle 55 so that the rollers 69 on the holder 50 engage the cup 35 and carry it upward.

The rollers 69 are mounted in three equidistantly spaced fingers on a floating portion 70 of said holder 50 resting on an equal number of springs 71 carried by the main portion 72 thereof which moves upward to a fixed height regardless of conditions. Screws 71' extending through the springs 71 and openings in the main portion 72 of said holder 50 from the floating portion 70 keep said movable portion in place when the cup 35 is not contacted.

The upward motion of the cup 35 first carries the edge thereof into contact with the leveling ring 73 which moves upward therewith and finally brings the reflector 41 on the inner surface of said cup 35 against the three equidistantly spaced rollers 74 of the centering and positioning means. As the top surface of the edge of the cup 35 is formed by pressure from the same die which forms the inner surface of said cup 35, the leveling ring 73 accurately defines the position taken by the reflecting surface 41. The leveling ring 73 is kept in place by a vertically positioned slide 75 (Figs. 4 and 5) which is located about vertical guide ways at opposite sides of the upwardly extending portion 76 of the bracket 77 which carry the ball bearings 78. The weight of the leveling ring 73 and slide 75 offers sufficient resistance to the upward movement of the cup 35 to cause it to tip until the rim 47 thereof engages all portions of the leveling ring 73 and, together with the slight friction produced in moving, is not so powerful as to hinder its upward movement appreciably. The rollers 74 are fastened to arms 79 extending from the bracket 80 encircling the leveling ring 73 and are held at exact positions in a plane parallel to said ring 73 and at the same distance from the vertical axis through the apparatus at this station, although said bracket 80 is movable vertically. As shown, said bracket 80 is mounted on a vertically posi-

tioned slide 81 which is located about V-shaped guide ways at opposite sides of the upwardly extending portion 76 of the bracket 77 which carry the ball bearings 78 and takes a vertical position determined by the adjustment of the screw 83. Rearwardly extending projections 84 on the slide 81 engage the fixed collars 85 and 86 on the screw 83 which is threaded into a rearwardly extending portion of the bracket 77. In some instances, it is also preferred that the orientation of the cup 35 be re-established as said cup 35 has now been moved away from the stationary holder 49 and accordingly a spring finger 87 is mounted on the leveling ring 73 as shown in Figs. 4 and 5 which presses against the side of either the depression or a protuberance in one portion of the rim 47 at a definite angular relation to the leads 36, 37, 38 and 39. To position the cup 35 properly against the end of the spring finger 87 requires that said cup be turned manually.

All portions of the head 40 are now functioning and all further operations occurring at station B are those performed by apparatus permanently mounted at that station. Such apparatus consists of the lead positioning means 89 shown in Figs. 4, 6 and 7 and the focus finding and cup repositioning apparatus 90 and 91 respectively of Fig. 4. The lead positioning means 89 serves to roughly position each of the leads 36, 37, 38 and 39 so that they are within the range of operations of other apparatus of the machine and is operated in combination with the focus finding apparatus 90. Both the lead positioning means 89 and the focus finding apparatus 90 are located above the plane of the indexing movement of the head 40 and are lowered into operative relation to the cup 35 therein by a downward motion of the slide 92 on which they are mounted. The slide 92 as shown in Figs. 4 and 6 is located in ways in a bracket 93 mounted at a fixed position on the table 94 which, in turn, is mounted on the rigid center post 57 of the frame of the machine and during its movement carries the block 95 which is attached thereto by bar 96 down onto the ends of the leads 36, 37, 38 and 39. Conical openings 97 are provided in the bottom of the block 95 in the areas within which the leads 36, 37, 38 and 39 fall and the full motion of said block 95 causes the ends of said leads to be gathered up and directed through the smaller portions of said openings 97 which position them. The ends of the leads 36, 37, 38 and 39 also enter the wadding 98 which is within the chamber 99 in the top of the block 95 and which distributes a lubricant over the surface thereof and pass into openings 100 in the cover plate 101 over said chamber 99. During the normal operation of the machine the lubricant is used up at a uniform rate and is automatically replenished from the supply held by the cup 102 which releases said lubricant at a given rate to the pipe 103 conducting it to said chamber 99. The cup 102 is mounted on the slide 92 and therefore remains at a fixed relation to the block 95 at all times. The block 95 also functions as a guard for the focus finding apparatus 90 which it partly surrounds and is provided with a plate 104 which shields the lower end of said apparatus. In instances when the head 40 is permitted to enter a second cycle of operations with the cup 35 operated on during the previous cycle, the filament mount thereof will be struck by the plate 104 and be pressed down out of position so that it may not strike

and injure the focus finding apparatus 90 or other parts of the machine.

The focus finding apparatus 90 is provided to ascertain the proper position in the cup 35 for the light sources and operates in combination with suitable repositioning apparatus 91 which adjusts the cup 35 vertically in the head 40 so that it assumes the correct relation to the devices at the other stations when indexed thereto. In this particular instance, the focus finding apparatus 90 is of the general type disclosed in Westerlund application Serial No. 291,722, filed August 24, 1939, and comprises the two photo-cells 105 and 106 (Figs. 6 and 8) which are mounted on the lower end of the spindle 107 carried by the extending arm 108 of slide 92. The photo-cells 105 and 106 are made by cutting, at 109, the photo sensitive layers on a single metal strip 110 which serves both to connect them in series electrically and to hold them in place. Other electrical connections are made to said photo-cells 105 and 106 through the shoes 111 below the screws 112 carried by the two straps 113 encircling the metal strip 110 and the spindle 107 and the wires 114 and 115 which are soldered to the back of said straps 113 and which extend upward through a central passage in said spindle 107. The straps 113 are separated from the spindle 107 by the bushings 118 of insulating material and are connected to the galvanometer 116 (Fig. 1) on a table 117 adjacent an operator. The spindle 107 is clamped to the arm 108 of the slide 92 by the nuts 119—119 and is orientated so that the photo-cells 105 and 106 face away from the center of the machine and the separation 109 therebetween is within the cup 35 and at a definite relation to the working plane of all mounting apparatus of the machine when said slide 92 is all the way down and the shoulder 120 rests on bracket 93.

The downward movement of the slide 92, which brings about the above described movements of the lead positioning means 89 and focus finding apparatus 90, is produced by self contained means within the apparatus at this station which is operated hydraulically from a source of oil at constant pressure. Such actuating means separates all strains of operation from the structure of the machine and allows maximum freedom of control. As shown, a movable cylinder 121 is attached to the slide 92 by the pin 122 and the stationary piston 123 working within said cylinder 121 is attached to a rod 124 extending up through the end 125 thereof to the cross bar 126 which joins two posts 127 extending upward from the bracket 93. The oil which forces the cylinder 121 and slide 92 down enters said cylinder 121 through the longitudinal passage 128 in the rod 124 which is fed by piping 129 leading to the control valve 130 as shown in Fig. 9. Oil must also escape from above the piston 123 and does so through the passage 131 in said piston 123 and rod 124 and returns to the control valve 130 through the piping 132. The timing of the operation of the hydraulic means depends on the operation of the control valve 130 which is mounted on the frame in such a position as to allow the cam 133 on the main cam shaft 67 to engage the roller 134 and move the valving pin 135 thereof. The high pressure oil connection is made to the valve 130 at 136 and the draining oil is taken therefrom at 137 and allowed to flow into a storage tank not shown in combination with the machine from which it is automatically returned to the high pressure 75

lines. It is very important that all oil be kept from the lamp parts and means are provided in trough 138 for catching any of such oil leaking out of the head of said cylinder 121 about the rod 124. This point is the only possible source of leakage and is drained through the pipe 139 which is attached to the cylinder end 125 and which telescopes the larger drain pipe 140 leading to the storage tank.

- 10 The function of the photo-cells 105 and 106 is to generate electrical currents proportionate to the amounts of light received from the reflector 41 of the cup 35 so that said currents indicate whether said cup 35 should be raised or lowered 15 to cause the reflector 41 to be properly positioned with respect to the working plane of the mounting apparatus. Ordinarily both photo-cells 105 and 106 receive equal amounts of light when the cup 35 and reflector 41 are correctly positioned. 20 The light is that emitted by a source 141 mounted directly over the cup 35 at a higher position than shown and redirected by the half of the reflector 41 on the outer side of the machine which 25 faces said photo-cells 105 and 106. The light source 141 in this instance is mounted on a very rigid structure carried by the posts 142 extending from the table 94 of the machine and directs the light downward in parallel rays which are 30 redirected by all portions of the reflector 41 in a like manner. It is not necessary that the photo-cells 105 and 106 scan the entire reflector 41 as the method of manufacture of the cup 35 and 35 said reflector 41 causes all variations affecting the length of focus thereof to occur in equal amounts in all side sections thereof. Should one of the photo-cells 105 and 106 be receiving more light than the other, the greater current generated thereby deflects the pointer of the galvanometer 116 (Fig. 1) to one side indicating 40 that the cup 35 must be adjusted vertically. The direction of the deflection of the pointer indicates the direction the adjustment must take and the operator turns the crank 143 of the positioning apparatus until the pointer is 45 brought to the center location. The crank 143 is mounted below the table 117 on the end of a flexible shaft 144 connecting it to the worm gear 145 and, when turned, rotates the gear 146, the shaft 147 and the screw 83 which is connected thereto through the inter-meshing gears 148 and 149 at this time. The shaft 147 is keyed 50 to the gear 146 and is slideable in said gear 146 and the bracket 150 in order that it can be raised to separate gear 148 from gear 149 during the 55 indexing period. During the operating period, the shaft 147 is positioned by the collar 151 thereon which rests on the cover 152 over the gear chamber in the bracket 150, and at other times the slide 92 of the focus finding apparatus 60 is in the up position and the arm 153 thereof is in engagement with the nuts 154 and the shaft 147 is held in the raised position shown. Following the positioning operation, the valve 130 is adjusted and the cylinder 121 and slide 92 are raised to the up position.

The indexing movement of the turret 56 carrying the head 40 from station B takes it to station C where the floating portion 70 of the holder 50 now supporting the cup 35 is immediately locked in place. The purpose of this locking operation is to block all action of the springs 71 which separate the floating and stationary portions 70 and 72 respectively of the holder 50 so that the cup 35 cannot be moved from engagement with the positioning means of the head 40 during the

operations of other apparatus at this station. The locking device 155 as shown in Figs. 1 and 10 consists of two spaced wedges 156—156 which are mounted on the bracket 157 on the outer end of a rod 158 extending from the cylinder 159 and is operated by movement of a piston within said cylinder 159 which is attached to the rod 158 and which moves said wedges 156—156 into position between the rollers 160 and 161 (Fig. 5) at opposite sides of the floating and stationary portions 70 and 72 respectively of the holder 50. The motion of the wedges 156—156 is caused by the entrance of compressed air into the head of the cylinder 159 from the pipe 162 and stops when said wedges 156—156 are tightly squeezed in-between the rollers 160 and 161. The cylinder 159 is mounted on the bracket 163 extending from the frame of the machine below the turret 56 and discharges air from behind the piston through the pipe 164. Both pipes 162 and 164 as shown in Fig. 9 are also connected to a four way valve 165 which is connected to the source of compressed air (not shown) through the pipe 166 and which discharges air through the port 167. At this time, the valving pin 168 is adjusted by the cam 169 on the shaft 67 so that pipe 162 receives compressed air from pipe 166 and the air being discharged through pipe 164 is opened to the atmosphere through port 167. A rod 170 extending from the bracket 163 parallel to rod 158 passes through an opening in bracket 157 and keeps said bracket 157 and the wedges 156—156 from turning out of position when said wedges are not engaged with the rollers 160 and 161. To prevent the wedges 156—156 from being forced in-between the rollers 160 and 161 too tightly and causing difficulty in withdrawing them, a spring 171 is mounted on the rod 170 behind the collar 172 thereon which engages and resists the bracket 157 at the latter part of its movement. The wedges 156—156 are pivoted on pins 173 carried by the bracket 157 and are under the influence of springs 174 about the upper end of said pins 173 which turn them so that the stop screws 175 on each are pressed against the bracket 157. If the wedges 156—156 should resist withdrawal from between the rollers 160 and 161 at the end of the cycle of operations of the apparatus at this station, the indexing motion of the head 40 which follows will only turn them about the pins 173 and no broken parts will result.

Following the locking of the holder 50 at station C, the leads 36, 38 and 39 are relocated and lead 31 is reformed by the bending device shown in Figs. 1, 11, 12 and 13. The relocating of the leads 36, 38 and 39 is performed by the die 176 which is attached to the slide 177 having rib or flange portions 171' which slide in the ways of the bracket 178 on the table 94 opposite this station (C) and is brought about by the downward movement thereof from a position above the path of travel of the head parts. At the time of operation, oil at pressure is introduced into the cylinder 179 below the piston therein and said cylinder 179 which is connected to the slide 177 through the plates 180, the springs 181 at opposite sides thereof and the plate 182, moves down with said slide 177. The cylinder 179 is also connected to the sub-slide 183 within the ways of the slide 177 by the pin 184 and the expansion force of the springs 181 keeps the cam 185 on the sub-slide 183 against the cover plate 186 over the ways therein so that no relative movement occurs between the slide 177 and sub-slide 183 at this time. The springs 181 are kept in proper alignment by 75

posts 187 attached to the plates 180 and extending through openings in the plate 182. The downward movement of the slide 177 lowers the die 176 onto the upper ends of the leads 36, 38 and 39 which are directed into the passages 188, 189 and 190 respectively therein by the conical lower portions thereof. In this particular instance, lead 36 is bent so as to take a vertical position $\frac{1}{2}$ of an inch outward from the machine from its former position and the leads 38 and 39 are bent so as to be nearer each other and take vertical positions inward toward the center of the machine from their supporting post 42. The downward movement of the slide 177 ends when the lower end of the screw 191 butts against the top surface 178' of bracket 178, although the cylinder 179 continues to move and moves the sub-slide 183 within its ways therein. The manner in which said screw 191 engages the bracket 178 may be better understood by reference to a similar arrangement shown in Fig. 24 where the screw 528 on slide 502 engages the top of bracket 503 to end downward movement of said slide 502.

During the separate movement of the sub-slide 183, the springs 181 are further compressed and cam 185 is lowered so that the tapered anvil 192 moves into position beside the lead 37 and the tool or wiper 193 swings down thereagainst to the positions shown in Figs. 12 and 13. The anvil 192 is mounted on the yoke 194 which is pivotally mounted on the pin 195 carried by slide 177 and swings down into position when the finger 196 which is attached to the cam 185 is lowered thereby. Since some variations occur in the position of the lead 37 in the different cups 35 introduced into the head 40, the anvil 192 which gradually increases in width moves in from the side until it is actually in contact with said lead 37 no matter what its position may be. The wiper 193 is pivotally mounted on the pin 197 extending from the slide 177 and is caused to swing over against the lead 37 by a corresponding movement of the block 198 which is also mounted on said pin 197 and which engages said wiper 193 through the spring 199. The spring 199 is located in a well in the block 198 and normally keeps the wiper 193 turned so that a heel 200 (Fig. 13) thereof rests against a portion of the block 198. The downward movement of the cam 185 also actuates the block 198 and therefore the wiper 193 as said movement carries the roller 201 on the upper end of the lever 202 into the sideward deflected portion of the cam slot 203 in said cam 185 and turns said lever 202 about the pin 204 extending from the slide 177. The lower end of the lever 202 in turn engages the pin 205 extending from the block 198 and turns it so that the lead 37 is bent over the anvil 192 as shown. During the bending operation, the end of the lead 37 falls against the side of the die 176 and into the groove therein and is bent both sideward toward lead 36 and upward to a vertical position. At the limit of motion, the spring 199 between the wiper 193 and the block 198 is further compressed in taking up the excessive motion of the latter.

The cylinder 179 corresponds to similar operating means at the other stations and is moved by the inflow of oil behind a piston (not shown) therein which is attached to the rod 207 mounted on the cross bar 208 extending between the upper ends of the posts 209. As in the other instances, the posts 209 are carried by the bracket 178 mounted on the table 94 and separate all operating strains from the machine proper and the

oil is conducted to and from the chambers above and below the piston by passages in the rod 287. At the start of the operating period, oil at pressure is introduced into the lower chamber through the pipes 210 and 129 which, as shown in Fig. 9, connect the rod 287 to the valve 130 and oil is discharged from the upper chamber through pipes 211 and 132 which connect said rod 287 to said control valve 130. Any leakage of oil is caught in the trough 212 in the head 213 of the cylinder 178 and is drained back to the source of supply (not shown) through pipe 214. No other operations are performed by the apparatus at this (C) station and said apparatus is returned to its earlier position by the adjustment of the control valve 130 by the cam 133. The oil under pressure then passes through pipe 211 and into the upper chamber in the cylinder 178 whereas the oil in the lower chamber is drained through pipe 210. The sub-slide 183, first, moves up to its prior relation to the slide 177 whereupon both the sub-slide 183 and slide 177 are moved upward as a unit. These operations cause the relocating and reshaping apparatus to disengage itself from the leads 36, 37, 38 and 39 without disturbing them in any way. The locking device 155 is also separated from the holder 50 of the head 40 at this time by an adjustment to the valve 165 (Fig. 9) which directs compressed air into the space behind the piston in the cylinder 159 through pipe 164 and allows the air on the opposite side of said piston to escape through pipe 162 and port 161.

An index of the turret 56 now occurs and the head 40 is carried to station D, the next in line, and into operative relation to a second locking device 215 and the final lead bending device 216. The locking device 215 is an exact duplicate of the device 155 located at station C and shown in detail in Fig. 10 and being connected to the valve 165 by the pipes 217-162 and 218-164 is operated in exactly the same manner. The lead bending device 216 on the other hand reforms the leads 36, 38 and 39 and, as shown in detail in Figs. 14, 15 and 16, correspond to the other devices only in that it is operated hydraulically through movement of the cylinder 219 and is supported entirely by a single bracket 220 mounted on the table 94 of the machine. The parts of the bending device 216 are first positioned in operative relation to the leads 36, 37, 38 and 39 by a downward movement of the cylinder 219 and the slide 221 which moves in ways in the bracket 220 and which receives its motion from the cylinder 219 through the plates 222 and the springs 223 on opposite sides thereof and the plate 224 attached to said slide 221. During the downward movement, the slide 221 carries the die 225 attached to the lower end thereof over the upright end of the lead 37 which passes up the V notch and opening 226 therein and a stop screw (not shown) on the plate 224 is carried against the bracket 220 which terminates the motion of said slide 221. The cylinder 219, however, continues to move and further compresses the springs 223 and shifts the subslide 227 to which it is connected by the pin 228 (Fig. 14) in the ways of the slide 221 in which it is located. Until this time the expansion force of the springs 223 has kept sub-slide 227 pulled upward so that the cam 229 thereon butts against the cover plate 230 over said sub-slide 227 but now said motion moves said cam 229 so that the anvil 231 drops into position between the leads 36 and 38-39 and so that the wipers 232 and 233 bend

said leads 36, 38 and 39. The anvil 231 is attached to the yoke 234 which is pivotally mounted on the pin 235 extending through the lower part of the slide 221 and swings into place by its own weight when permitted by the link 236 connecting said yoke 234 to the bracket 237 on the cam 229. The position of the leads 36 and 38-39 vary somewhat in different cups 35 and the tapered end of the anvil 231 as shown in dotted lines in Fig. 16 must move until all space therebetween is filled by said anvil 231 and may cause the yoke 234 to shift longitudinally on the pin 235 until both sides of said anvil 231 are against said leads 36 and 38-39. Further movement of the cam 229 drops the wedges 238-239 (Figs. 14 and 15), which are similar in construction and are located on opposite sides of the slide 221 and which project over the cam 229 at 240, in-between said slide 221 and the yoke 234 so that the anvil 231 cannot shift sideward hereafter. Still further movement of the cam 229 carries the rollers 241-241' into the angular portion of the cam slots 242-242' and causes the levers 243-243' on which said rollers 241-241' are mounted to swing the blocks 244-245 and tools or wipers 232 and 233 respectively against the leads 36 and 38-39 respectively. The levers 243-243' are mounted on pins 246-246' extending from the slide 221 and engage the pins 247-247' respectively extending from the blocks 244 and 245 respectively which turn about the pins 248 and 248' extending from the slide 221. The wiper 232 is separated from block 244 by the spring 249 which is largely contained within a well therein and, in turning, causes the lead 36 to be bent to a horizontal position over the anvil 231 and an end-most portion thereof to fall into a groove in the die 225 and be bent to a vertical position. The wiper 233 is separated from block 245 by the spring 250 which is largely contained in a well therein and, in turning, causes both leads 38 and 39 to be bent to a horizontal position over the anvil 231 and an end portion of each to be carried into separate grooves in the die 225 and to be bent at two differently situated points to a vertical position. Slight notches at the edges of the blocks 244 and 245 and the wipers 232 and 233 assist these parts to bend the leads in the proper manner. A bar 251 joins the pins 248 and 248' and stiffens the mounting for the wipers 232 and 233 which are kept from swinging away from the blocks 244 and 245 under the influence of the springs 249 and 250 respectively during rest periods of the device by heel portions thereof (not shown) engaging said blocks 244 and 245. No further downward movement of the slide 221 and cam 229 occurs and cylinder 219 is caused to return upward to its former position to separate the bending device 216 from the leads 36, 37, 38 and 39 and complete the cycle of operation thereof. The return movement of the parts of the device occurs in exactly the reverse order to the prior movements thereof and swings the blocks 244 and 245 outward until they rest against the fingers 252 and 252' on the side of the slide 221.

During the first part of the cycle of operation of the bending device, oil at pressure is conducted from the control valve 130 (Fig. 9) to the chamber below the piston (not shown) in the cylinder 219 by the pipes 129 and 253 and a passage in the rod 254 and is discharged from the chamber above said piston through a second passage in rod 254 and the pipes 255 and 132 to said valve 130. The rod 254 and piston are fixed members

since the former is attached to the cross bar 256 extending between the posts 257 carried by the bracket 220. The return motion of the cylinder 219 is brought about by a reversal of the oil connections thereto caused by the readjustment of the valve 130. As in prior instances, the leakage about the rod 254 is caught in a trough 258 in the upper head 259 of the cylinder 219 and is returned to the storage tank through pipe 260. The plate 261 on the head 259 engages one of the side rods 257 which functions as a guide to hold the upper end of the cylinder 219 in alignment with the other apparatus of the bending device 216. Before the head 40 and cup 35 are indexed to the next station, the locking device 215 is separated from the holder 50 by the readjustment of the valve 165.

Station E is the next station taken by the head 40 in its next regular index and is occupied by the trimming device 262 (Figs. 1, 17 and 18) which cuts all of the leads 36, 37, 38 and 39 to length. In this instance, the die 263 is carried down over the upper ends of the leads 36, 37, 38 and 39 which pass up into apertures therein and the cutting die 264 is moved sideward in a manner cutting the ends thereof protruding through said die 263. The die 263 is attached to the lower end of the slide 265 and through the cover plate 266, spring 267 and the sub-slide 268 to the cylinder 269 which corresponds to the cylinder of the operating apparatus of the other devices already described. As in such devices, the cylinder 269 is moved with respect to a piston indirectly supported on the posts 270 extending upward from the bracket 271 and is under the control of the valve 130 as shown in Fig. 9 which directs the flow of oil at pressure thereto. The oil flows to the cylinder 269 through pipes 272 and 129 and is drained therefrom through pipes 273 and 132 at this time. The slide 265 is located in ways of the bracket 271 which is mounted at a fixed position on the table 94 of the machine and is moved downward by a similar motion of the cylinder 269 because the tension in the spring 267, which extends between a post in the sub-slide 268 and the cover plate 266 over the ways thereof in said slide 265, keeps the shoulder 274 of said sub-slide 268 against a portion of said slide 265. The die 263 is properly positioned over the ends of the leads 36, 37, 38 and 39 when a stop screw 275 in the back of the slide 265 butts against the bracket 271 and terminates the movement of said slide 265. Further movement of the cylinder 269 carries the sub-slide 268 down alone and the angular cam surface 276 thereof against the roller 277 on the lever 278 which is caused to move the cutting die 264 along the surface of the die 263 and against the leads 36, 37, 38 and 39 protruding thereabove. The lever 278 is supported on a pin 279 carried by the bracket 280 which is attached to the portion 281 of the slide 265 forming the ways for the cutting die 264 and moves said cutting die 264 only sufficiently to trim the leads. During the latter part of the downward movement of the slide 265, the gate 282 which is located in ways below the plates 283 on one side thereof is shifted so that it closes the open end of the ways containing the cutting die 264 and keeps the trimmings from the leads 36, 37, 38 and 39 therein. This motion of the gate 282 results when the screw 284 engages the terminus of the pipe 285 which is located in the opening 286 in the gate 282 and which is flush with the adjacent face of the slide 265.

The return upward movement of the slide 265 and sub-slide 268 now occurs and cutting die 264, die 263 and gate 282 are returned to their former position in order. The cutting die 264 is normally pulled back by the return motion of the lever 278 produced by the uncoiling force of the spring 287 when the sub-slide 268 is moved but may not move until the upward motion of the slide 265 carries the roller 277 on said lever 278 against the cam 288 carried by the bracket 271. The spring 287 is coiled around the pin 279 and engages the bracket 280 and a post extending from the lever 278. The return movement of die 263 is necessarily that of the slide 265 which also carries the gate 282 upward until the pipe 285 reaches the end of the opening 286 therein and causes said gate 282 to shift. At such times, the open end of the ways for die 264 containing the trimmings passes into alignment with the pipe 285 and, shortly thereafter, during the indexing interval of the head 40, a stream of air is blown from the slot 289 of the second pipe 290 and said trimmings are sucked into said pipe 285. The air producing the suction is released by the valve 291 (Fig. 1) which is mounted at a fixed position adjacent the rim of the turret 56 and is operated by the momentary engagement of the circular plate 54 of a head 40 with the control lever 292 of the valve 291 during the indexing period. The pipe 290 is connected directly to the valve 291 and has one end, which is plugged except for slot 289, soldered in the terminus of pipe 285. The suction produced draws air in through the opening 293 above the cutting die 264, the V slot 294 therein which is now partially withdrawn from the ways in the portion 281 of slide 265 and the apertures in the die 263 and carries the trimmings into the air stream which blows them down the pipe 285 to the cage 295 (Fig. 1). The cage 295 in turn is made of wire screen and retains the trimmings but allows the air to escape.

The next station taken by the head 40 is station F and is occupied by the device 296 shown in detail in Figs. 19, 20 and 21 which displaces the metal in the ends of the leads 37 and 38 so that longitudinal grooves are provided therein in which the ends of a wire filament can be clamped. The operation of the device 296 starts with the downward motion of the die 297 which positions it in operative relation to the leads 37 and 38 and which is the result of a movement of the slide 298, to which said die 297 is attached, in ways of the bracket 299 on the table 94 of the machine adjacent this station. The slide 298 is connected to the cylinder 300 of the usual hydraulic operating means provided for each of the various devices of the machine through the rods 301 and springs 302 at opposite sides thereof, the pin 303, the pneumatic hammering mechanism 304 and pin 305 and like said means is moved by the flow of oil thereto from the control valve 130 (Fig. 9). The oil is received in the chamber formed by the cylinder 300 and a piston 306 therein which is attached to the rod 307 and which is held stationary as in prior instances by means including the posts 308 extending from the bracket 299. The die 297 takes the correct relation to the leads 37 and 38 when a stop screw (not shown) on the back of slide 298 is brought into engagement with the bracket 299 at which time the end of the lead 39 is contained within the opening 309 in said die 297 and the ends of the leads 37 and 38 are located in the grooves 310 and 311 respectively at opposite sides of said

die 297 and butt against the pins 312 and 313 (Fig. 20) respectively.

The pins 312 and 313 position the leads 37 and 38 within the grooves 310 and 311 of the die 297 and correct any longitudinal displacement thereof and are mounted on an inwardly projecting portion 314 of the slide 315 (Fig. 19) which is located in the ways formed on bracket 316 by the gibs 317. The bracket 316 is attached to the outer end of the post 318 extending from the slide 298 and can be turned about said post 318 to bring the pins 312 and 313 into alignment with the grooves 310 and 311 respectively in said die 297 by turning the screw 319 on the arm 320 extending from said slide 298 and the screws 321—321 abutting against said die 297. As the slide 298 and die 297 are moved into position, the screw 322 on the upper end of the slide 315 engages the arm 323 on the shaft 324 and turns said shaft 324 until the arm 325 thereon strikes the stop screw 326. No further downward movement of the slide 315 and the pins 312 and 313, which are located at a definite position, can occur as the shaft 324 and the stop screw 326 are held in a fixed position by the bracket 327 which is attached to bracket 299.

The punches 328 and 329, which cooperate with the die 297 in forming the ends of the leads 37 and 38, are held by the jaws 330 and 331 respectively which are pivoted on the post 318 and are therefore brought into operative relation to said leads 37 and 38 by the downward motion of the slide 298. Further downward movement of the cylinder 300 and the pneumatic hammering mechanism 304 however occurs and causes a corresponding movement of the sub-slide 332 which is located in ways below the plate 333 in the slide 298 and which is connected to the pneumatic hammering mechanism 304 by the pin 303. The separate motion of the sub-slide 332, which is against the contracting force of the springs 302, first, lifts the positioning pins 312 and 313 from the grooves 310 and 311 in the die 297 and, then, causes the punches 328 and 329 to enter said grooves 310 and 311 and reshape the leads 37 and 38. At the start of the movement of the sub-slide 332, the cam 334 which is mounted on the pins 335 and 336 extending therefrom is moved so that one edge engages the roller 337 on one arm of the lever 325 and turns said lever 325, the shaft 324 and arm 323. The arm 323, in turn, moves the slide 315 upward in the ways of the now stationary bracket 316 against the contracting force of the spring 338 and so provides for the movement of the pins 312 and 313 attached thereto. The punches 328 and 329 are actuated through the jaws 330 and 331 by the wedging action of the lower end 339 of the sub-slide 332 which now passes between the rollers 340—340 on the upper ends thereof. The rollers 340—340 are mounted on one end of the pins 341—341 held by the jaws 330 and 331 and correspond to a second pair of rollers 342—342 (Fig. 19) on the opposite ends of said pins 341—341. These rollers 342—342 are located in the slots 343—343 of the cam 334 which are shaped so as not to interfere with the movements of said rollers 342—342 during the downward movement of the cam 334 and the sub-slide 332. A metal strap 344 mounted on the outer ends of the pins 341 slides along the face of the cam 334 during the movements thereof and assists in keeping said cam 334 and the upper ends of the jaws 330 and 331 in proper relation to each other at all times. The movement of the cylinder

300 ends when the lower portion thereof comes to rest on the top of one of the rods 301 and the guide 345 comes to rest on the other of said rods 301 and is not ordinarily subject to adjustment. 5 If an adjustment is required as to the depth of the penetration of the punches 328 and 329 into the leads 37 and 38, the length of said punches 328 and 329 is changed by slipping shims in or out of the space between them and the heels 346 10 of the jaws 330 and 331. The punches 328 and 329 are kept from shifting sideward by the blocks 347 which are clamped thereagainst by the screws 348.

When the wedge shaped ends 349 of the punches 328 and 329 have contacted the ends of the leads 37 and 38, the pneumatic hammering mechanism 304 is brought into operation and the additional swaging or hammering action thereof is caused to force said ends 349 into the leads 37 and 38 which are displaced into the grooves 310 and 311 of the die 297. The pneumatic hammering mechanism 304 is a unit manufactured on a commercial scale by the Chicago Pneumatic Tool Company of Chicago, Illinois, and is operated from an external source of compressed air. The compressed air enters the unit 304 through a flexible hose 350 connected, as shown in Fig. 9, to the valve 351 which is operated electrically by the flow of current through the solenoid 352 thereof and which is under control of the mercury switch 353 (Figs. 1, 9 and 19) mounted on one of the posts 308 adjacent the cylinder 300. When the final movement of the cylinder 300 occurs, 20 the rod 354, which is mounted on the guide 345 from an external source of compressed air. The compressed air enters the unit 304 through a flexible hose 350 connected, as shown in Fig. 9, to the valve 351 which is operated electrically by the flow of current through the solenoid 352 thereof and which is under control of the mercury switch 353 (Figs. 1, 9 and 19) mounted on one of the posts 308 adjacent the cylinder 300. When the final movement of the cylinder 300 occurs, the rod 354, which is mounted on the guide 345 carried by said cylinder 300 is moved down away from the arm 355 and the mercury switch 353 which is attached to the arm 355 on the opposite end of the pin 357 from the first arm 355 tips, closing the circuit to solenoid 352. The pin 357 30 is mounted in a block 358 clamped to one of the posts 308 which is located in a slot in the guide 345 and is turned by the eccentric position of the weight of the arms 355 and 356 when the rod 354 is withdrawn. The arm 355 does not interfere with the motion of the rod 354 either during the downward or upward movements thereof and tips the mercury switch 353 to the open position when in engagement therewith. As shown in Fig. 9, both the solenoid 352 and the mercury switch 353 are preferably connected in series with a second mercury switch 359 which takes a closed position only when a cup 35 is located at this (F) station. The mercury switch 359 as shown in Figs. 1 and 19 is mounted on block 360 which is carried by the rotatable shaft 361 in the end of the arm 362 extending from the bracket 299 and is tilted so as to complete the circuit therethrough by movement of the arm 363 when the cup 35 is indexed against the shoe 364 on the lower end thereof. The parts of the device 40 operating with the mercury switch 359 correspond to similar apparatus at a succeeding station which are shown more clearly in Fig. 22. When the cup 35 is not correctly positioned at station F, that is, when the cup 35 is not carried by the head 40, the weight of the arm 363 and the shoe 364 turns the shaft 361 until the stop screw 365 rests on the flange 366 of arm 362 and the mercury switch 359 is tilted so as to break the circuit therethrough and prevents operation of the pneumatic hammering mechanism. In many instances, the added force of the pneumatic hammering mechanism 304 is not required to cause the displacement of the leads and need not be included in the device 298. If the leads are made

of nickel, for instance, the hammering mechanism 304 and the control means therefore would not be required and the cylinder 300 could be connected directly to the sub-slide 332.

When the working parts have completed their cycle of operation and must be returned to their original positions, the control valve 130 is adjusted and the cylinder 300 moves upward. This movement of the cylinder 300 returns the parts of the device 296 in reverse order, the first movements being the separation of the punches 328 and 329 from the leads 37 and 38 whereupon the pins 312 and 313 are lowered onto the ends thereof. Both movements are the result of the upward motion of the cam 334 which carries the rollers 342 into a different portion of the slots 343 therein causing the jaws 330 and 331 to open and which carries the rim of said cam 334 away from the roller 337 so that arm 323 drops and the slide 315 and pins 312 and 313 are permitted to move down. The contracting force of the spring 338 which extends between posts in the bracket 316 and slide 315 produces the moving force for the latter. The leads 37 and 38 are not separated from the grooves 310 and 311 of the die 297 until it is carried upward by the motion of slide 298, at which time, the added pressure of the pins 312 and 313 on the ends thereof keeps said leads 37 and 38 from moving with said die 297. This method of operation prevents the leads 37 and 38 from being pulled out of shape should they tend to adhere to said die 297 since the pins 312 and 313 remain stationary and prevent any movement thereof until separation has occurred. During the first upward movement of the die 297 and the slide 298, the slide 315 moves in the bracket 316 but finally comes to rest on the top of said bracket 316 and is carried up away from the cup 35 with said die 297 and said slide 298.

The indexing motion of the turret 56 now occurs and the cup 35 and the head 40 are carried into station G, the next in order, which is occupied by a duplicate device 367 to that (296) at station F except that leads 36 and 39 are treated thereby. As in the prior instance the parts of the device 367 are carried into operative relation to the cup 35 by a movement of a slide, in this case the slide 298' as shown in Fig. 23, which supports the die 368 and the jaws 330' and 331' carrying the punches 369 and 370 respectively. The direction of movement of the slide 298' is downward and carries the die 368 down over the end of the lead 37 which passes into the opening therein and the ends of the leads 36 and 39 which pass into the grooves 371 and 372 respectively. As before, the leads to be reshaped are positioned by pins temporarily located within the upper part of the grooves 371 and 372 and attached to an extending portion 314' of the slide 315' which in turn is located in ways on the bracket 316' formed by the gibs 317'. Subsequent operations of the device 367 moves the slide 315' upward withdrawing the positioning pins from the grooves 371 and 372 and closes the jaws 330' and 331' causing the punches 369 and 370 to engage the leads 36 and 39. Following these operations, the device 367 returns to its original position in the same manner and sequence of operations as the earlier device.

The device 367 at station G is also preferably provided with pneumatic hammering mechanism and control apparatus therefor but only the means of feeling for the cup 35 is shown separated from Fig. 1. This means appears in Fig. 22 and comprises the shoe 364' on the pivoted

arm 363' which feel for the cup 35 and the mercury switch 359' which is tipped thereby and makes and breaks the control circuit. A single shaft 361' carried by the arm 362' extending from a bracket (not shown) on the table 94 supports both the arm 363' and the mercury switch 359'. The actuating cylinder 300', the pneumatic hammering mechanism 304', the control mercury switches 353' and 359' and the air control valve 351' of this device 367 appears in Fig. 9.

The next succeeding indexing movement carries the cup 35 and the head 40 into station H and into position before filament mounting apparatus which advances a coiled filament into proper relation to the reflecting surface 41 of the cup 35 and the leads 36 and 39 and then clamps said filament to the latter. Such apparatus corresponds to duplicate apparatus at station J, the next in line, which causes a second filament to be mounted on the leads 37 and 38 and like said apparatus is supplied with filaments by the operator seated adjacent the recess or concavity in the table 117 midway therebetween. The filaments first appear on the table 117 in a disarranged pile and are shifted about until free of each other by tweezers in the hand of the operator who then places single filaments on the holders 374 of the turrets 375 and 376. In their regular order of movement, the turrets 375 and 376 are indexed in a counterclockwise direction and present all the holders 374 in turn to the operator who usually places filaments in a group of first one and then the other thereof. The cup repositioning apparatus at station B is also adjusted by the operator who turns the crank 143 thereof according to readings given by the galvanometer 116. Each of the holders 374, as shown in detail in Figs. 24 and 25, has a raised center portion 377 with a groove 378 thereacross for positioning the coiled center portion 379 of the filament 380 and the offset slots 381 and 382 at opposite ends of said groove for receiving and positioning the ends of the legs 383 of said filament 380. The shoulders 384 at the inner end of the slots 381 and 382 engage the adjacent sides of the legs 383 of said filament 380 which in this particular instance are offset from the coiled portion 379 thereof at 385 and establish the position thereof. Since both turrets 375 and 376 are alike and all other apparatus at stations H and J are almost exact duplicates, all the following description is limited to the apparatus at station H but could as well be applied to that at station J.

The function of the turret 375 is to advance separate filaments to station X, the pick-up station for a separate transfer device 386 (Figs. 1 and 24), as they are needed and is brought about by indexing movements of said turret 375 in a clockwise direction which move each of the holders 374 in turn to said station. The transfer device 386 carries the filaments separately from station X to mounting relation to the leads 36 and 39 of the cup 35 at station H where the grooves therein are closed about the legs 383 of said filaments by the clamping device 387 permanently mounted thereat.

The turret 375 is fastened to a vertical shaft 388 (Figs. 24 and 26) carried by bearings within the bracket 389 and advances a holder 374 supporting a filament 380 to the pick-up station X at the moment the head 40, which carries the cup 35 in which the filament is to be mounted, is indexed from station G. At this particular moment, the preceding head 40 on the turret

56 is indexed out of station H and the circular plate 54 thereof is carried away from the roller 390 on the arm 391 so that it swings inward and causes the turret 375 to turn. The motion of the arm 391 is carried to the turret 375 through the vertical shaft 392, arm 393, linkage 394, the arm 395 and the pawl 396 thereon which engages the teeth of the ratchet wheel 397 attached to the lower part of said turret 375 and is brought about by the contracting force of the spring 398. In order that the filament carrying holder 374 of the turret 375 will not advance beyond station X, the motion thereof is limited to that of carrying the collar 399 on the shaft 392 into engagement with the stop screw 400 (Fig. 26) on the bracket 389 and is prevented from overrunning that of the pawl 396 by the friction produced by levers 401 and 402 (Fig. 26). The friction levers 401 and 402 have fiber ends engaging the upper and lower surfaces of the ratchet wheel 397 and are pivotally mounted on the pins 405 and 406 respectively carried by the bracket 389 so that they can be drawn against said ratchet wheel 397 by the contracting force of the spring 407. The spring 407 bears against lever 402 and the nut 408 on the end of the stud 409 extending from lever 401. The return movement of the indexing means occurs when a head 40 again passes into station H as the circular plate 54 thereof forces the roller 390 and arm 391 back and the pawl 396 is carried into another notch in the ratchet wheel 397. During this interval, the turret 375 is held in a fixed position by the combined efforts of the friction levers 401 and 402 and the stationary pawl 410 which is pivotally mounted on the pin 411 extending from bracket 389. A spring 412 extending between posts in the pawls 396 and 410 keeps said pawl 410 against the ratchet wheel 397 at all times. On occasions a cup 35 is not carried by the head 40 entering station H and a filament 380 cannot be mounted. In such instances, the indexing means of the turret 375 is made inoperative while the head 40 is still at station G so that a holder 374 already relieved of its filament 380 remains at station X and the transferring device 386 cannot pick up a second filament 380 therefrom. The cup 35 ordinarily taking station G, the station preceding the mounting station, contacts the finger 413 (Figs. 22 and 24) and turns the arm 414 so that the stop pin 415 in the path of the screw 416 on the arm 395 of the indexing means for turret 375 is drawn down out of the path of movement thereof but, if no cup 35 is present, the pin 415 stays in the up position and said indexing means cannot operate. The pin 415 is connected to arm 414 through the link 417, the arm 418 and shaft 419 which is supported by the bracket 420 on one portion of the frame and is under the influence of spring 421. Stop screws on the collar 422 carried by the shaft 419 limit the motion of the stop pin 415 and the finger 413 by engaging a protruding portion 423 of the bracket 420.

The transferring device 386 appears in Figs. 24 and 27 and, at the beginning of the cycle of operation, holds the jaws 424 and 425 directly above the holder 374 at station X. The jaw 424 is movable with respect to jaw 425 as the major portion 426 thereof is located in slide ways of said jaw 425, whereas, jaw 425 is attached to the arm 427 extending from the bracket 428 on the end of the spindle 429 by the screws 430 which pass through slots in the major portion 426 of the jaw 424. The jaws 424 and 425 are first carried downward by a corresponding movement of the 75

spindle 429 caused by the flow of oil into the cylinder 431 on the upper end thereof and in so doing advance the tapered end of the pin 432 held by the arm 427 into one of the holes 433 of the turret 375. This operation positions the jaws 424 and 425 accurately over the holder 374 and the filament 380 thereon and it is not until said jaws 424 and 425 come to rest on the raised portion 377 of said holder 374 that they are positioned accurately in a vertical direction. The jaws 424 and 425 are shown in detail in Figs. 28, 29 and 30 and are both slotted at 434 to clear the ridge 435 on the holder 374 and extend downward on opposite sides of the raised portion 377 thereof. In the closing movement of the jaw 424, which is now brought about the V slotted ends of the locating fingers 436 and 437 on the block 438 first engage the legs 383 of the filament 380 whereupon the horizontal V groove 439 engages 10 and traps the coiled center portion 379 thereof. The fingers 436 and 437 are part of the block 438 fastened to the back of the jaw 424 and pass under portions of the jaw 425 which cooperate with similar portions on said jaw 424 in gripping and holding said legs 383 in position. 15 The coiled portion of the filament 380 and the grooved portion of the jaw 424 enters a horizontal cavity 440 in the jaw 425 which traps it and prevents any movement whatever.

Both the downward and closing movements of the jaws 424 and 425 are brought about hydraulically and are independent of each other in that they are under the control of the cams 441 and 442 respectively (Fig. 9) on the main cam shaft 35 447. The cam 442 adjusts the valve 443 so that air at pressure is permitted to pass from the pipe connection 444 of the supply source to the pipe 445 leading to the metal bellows 446 on the movable arm 427. The pipe 445 is connected to a portion of the head 447 of the bellows 446 supported by a pin 448 also extending through the lever 449 and into slots in the links 450 on opposite sides thereof and is comprised of one flexible section of rubber hose to avoid interference with the movements of the jaws 424 and 425 and other apparatus. The opposite head of the bellows 446 is held at a fixed distance from the arm 427 by the links 450 which are pivoted on the pin 451 carried thereby and which engage the pin 452 extending from directly opposite points on said head. When air enters the bellows 446, the expansion thereof moves the pin 448 in the slots in the links 450 and turns the lever 449 which is mounted on the shaft 453 so that the arm 454 on the opposite end of said shaft 453 moves the jaw 424 to the closed position. The connection between the arm 454 and the jaw 424 is made through the side extension 455 of the former which engages a sideward projecting arm 456 of the back portion 426 of said jaw 424 extending through a slot in the surrounding portions of both the jaw 425 and the arm 427. The springs 457 which extend between both ends of the pin 448 and the pins 452 are expanded during this interval and provide the means of separating the jaws 424 and 425 when the air within the bellows 446 is released. The hydraulic means controlled by the cam 441 is actuated by oil under pressure introduced to the apparatus through pipe 458 and valve 459 (Fig. 9), the latter of which is now adjusted by the cam 441 so that said oil flows from pipe 458 to pipe 460 and through pipe 461, pressure relief valve 462, pipe 463 and passage 464 in rod 465 to the cylinder 431. A tapered pin 466 joints the cylinder 431 to the spindle 429.

and is drawn tight in the openings in each by the spring 467 so that there is no "play" or difference in movement therebetween. As in prior instances, the rod 465 is fastened to a cross bar 468 extending between two vertical posts 469 and is stationary and the oil above the piston 470 on the lower end of said rod 465 is discharged from the cylinder 431 through the passage 471 in said piston 470 and said rod 465, the pipe 472, control valve 459 and pipe 473 to the supply tank (not shown). Since the momentum of the jaws 424 and 425 and other downwardly moving apparatus is relatively great, resilient stop means is provided for terminating said motion. This stop means comprises the pin 474 (Fig. 24) which rests on the metal plate on top of the rubber block 475 and which is slideable in the bracket 476 holding said block 475 and is engaged by the roller 477 on the back of the bracket 428 which comes to rest on the top end of said pin 474. The bracket 476 is a stationary member as it is securely fastened to the rim of the table 94. In addition to absorbing the shock of the stop, the resiliency of the stop means also allows the jaws 424 and 425 to be moved down until they rest on the raised portion 377 of the holder 374 and are correctly positioned with respect to the filament 380 thereon.

After the filament 380 is gripped by the jaws 424 and 425, the transfer arm 427 is raised to separate said jaws 424 and 425 and the locating pin 432 from the filament feeding turret 375, and is turned in a clockwise direction to place said jaws over station H. The end of the transfer arm 427 passes between parts of the clamping device 387 which is already in its cycle of operation and is lowered to position said filament 380 properly with respect to the leads 36 and 39. The raising and lowering movements are due to properly timed adjustments of the control valve 459 which first causes oil to flow into the cylinder 431 above the piston 470 and then reverses the connections causing the oil to flow into the space below the piston 470 in the cylinder 431. The turning movement is produced by separate apparatus engaging the bracket 428 and consists of the split sleeve 478 clamped to the lower end of the sleeve 479 surrounding the spline 429 and the hydraulically actuated vane 480 within the circular chamber 481 of the housing 482. The split sleeve 478 engages the bracket 428 through the bar 483 which extends into slide ways therein and is turned by the flow of oil into the chamber 481 from the pipe 484 under the control of valve 485. The back portion of the chamber 481 is filled by the circular segment 486 and the oil flows into one half thereof sealed from the remainder by the vanes 480 and 487. The vanes 480 and 487 are held in grooves in a portion 488 of the sleeve 479 and are backed by springs (not shown) which cause them to engage the circumference of the chamber 481 in housing 482. Oil is also present at the opposite side of the vanes 480 and 487 and is discharged to the supply tank (not shown) through the pipe 489, the valve 485 (Fig. 9) and pipe 490. The valve 485 is operated by cam 491 and receives the oil at pressure from the pipe 492. At the start of the rotative movement of the transferring device 386, the stop screw 493 held by the split sleeve 478 is against the lug 494 extending from the bracket 495 and the motion is continued until the stop screw 496 engages the opposite side of said lug 494. At this latter time, the jaws 424 and 425 are only roughly located with respect to the cup 35 and the lowering move-

ment thereof which follows carries the tapered end of the pin 432 of said transfer arm 427 into the hole of the locator 497 (Figs. 31 and 32) held by the clamping device 387 at station H. The legs 383 of the filament 380 held by the transfer jaws 424 and 425 are then in alignment with the V groove in the leads 36 and 39 and are carried thereinto by additional downward movement of said jaws 424 and 425 which positions the coiled portion 379 of said filament 380 at exactly the correct distance from the reflector 41 on the cup 35. This latter position of the arm 427 is established when the piston 470 engages the upper head 498 of the oil cylinder 431. During the swinging movement of the arm 427, the roller 477 on the bracket 428 passes over the cam 499 (Fig. 27) on the rim of the table 94 and prevents said arm 427 from moving downward until the jaws 424 and 425 are over station H. Only faulty operation of the device could cause the arm 427 to move downward ahead of time but, if allowed, would cause the transfer device 386 and the clamping device 387 to strike each other and one or the other to be broken. The V grooves in the leads 36 and 39 are closed around the ends of the filament 380 by the clamping device 387 which begins its cycle of operation when the head 40 reaches station H and the transfer device 386 is picking up the filament 380 from the turret 375. As shown in Figs. 24, 31, 32 and 33, the clamping device 387 corresponds to the various other devices at the other stations in that the main parts thereof, the jaws 500 and 501, are carried on a slide 502 within ways of the bracket 503 attached to the table 94 and are actuated by movement of the cylinder 504 with respect to a piston therein. The slide 502 provides ways for a subslide 505 which is connected to the cylinder 504 by the pin 506 and, at the start of the operating period, is kept up in said ways by the expanding force of the springs 507 on the rods 508 at opposite sides of the cylinder 504. The springs 507 rest on the fixed nuts on the rods 508 which are fastened to a cross plate 509 on the upper end of the slide 502 and butt against the plate 510 on the top end of the cylinder 504 which slidably engages said rods 508. At the start of the cycle of operation of the clamping device 387, the stop screw 511 on plate 509 is kept against the upper edge of the cam 512 on the lower end of the sub-slide 505 by the expanding force of the springs 507 and all parts of the device are located above the head 40 so as not to interfere with the indexing movements thereof.

The clamping device 387 is first moved down into operative relation to the leads 36 and 39 of the cup 35 by the corresponding movement of the slide 502 and the cylinder 504 caused by the flow of oil at pressure into the chamber below the piston 513 (Fig. 9) in the cylinder 504. The oil flow is under the control of the valve 514 which is adjusted by the cam 515 on the cam shaft 67 so that oil, taken from the source thereof by pipe 516, passes through said valve 514, the pipe 517 and the passage in rod 518 and piston 513 to the lower end of the cylinder 504. The oil above the piston 513 is forced out of the cylinder 504 through a second passage in the rod 518, pipe 519, valve 520, pipe 521, valve 522, pipe 523, the valve 514 and pipe 524 to the storage tank (not shown) at the same time. The check valve 525 which is connected to pipe 521 and pipe 523 does not permit oil to flow from the direction of valve 520 and remains in the closed position during this interval. The piston 513 and the rod 518 are held

stationary by the bar 526 which is attached to the latter and surmounts the posts 527—527 extending from the bracket 503. The downward movement of the cylinder 504 moves the slide 502 and sub-slide 505 correspondingly as a single unit until the clamping jaws 500 and 501 are brought into operative relation to the leads 36 and 39 whereupon the stop screw 528 comes in contact with the upper surface 503' of the bracket 503 and said sub-slide 505 moves separately. The jaws 500 and 501 are mounted on the pin 529 extending from the slide 502 and are positioned when the motion of said slide 502 is ended.

The separate motion of the sub-slide 505 brings about a positioning operation of the clamping device 387, in preparation to the delivery motion of the transfer device 386 which places the legs 383 of the filament 380 in the grooves of said leads 36 and 39, and stops all other operations of the clamping device 387 until said filament 380 takes said position. The sub-slide 505 is located in ways in the slide 502 in which it is held by the plates 530—530 at opposite sides thereof which enter longitudinal grooves therein and moves the cam 512 so that the rollers 531—531 on the pins 532—532 in the upper ends of the jaws 500 and 501 are carried into different parts of the channels 533—533 therein. The jaws 500 and 501 are partly closed by this action and carry the slides 534—535 in the ways of the plates 536—536 over the die blocks 537—538 respectively against the leads 36 and 39. During this interval, both slides 534 and 535 are kept in a forward position in said ways by the levers 539 and 540 which are also pivoted on the pin 529 as the spring 541 extending between ears of said levers 539 and 540 keeps them tight against the backs of said jaws 500 and 501. When the leads 36 and 39 are engaged by both slides 534 and 535 and are correctly positioned, the screws 542 in a second set of ears on the levers 539 and 540 engage the extending lug 543 of slide 502 and prevent any further motion.

Immediately after the leads 36 and 39 are positioned, the movements of the jaws 500 and 501 and the sub-slide 505 stop as the mercury switch 544 adjacent the cylinder 504 is tipped and the valve 522 (Fig. 9) controlling the flow of oil from said cylinder 504 is closed. The mercury switch 544 is mounted on one end of a pin (not shown) pivoted in the blocks 545 clamped to the post 527 and, up until this time, is held at an angle keeping it from closing the circuit therethrough by the arm 546 on the opposite end of the pin (not shown) in the blocks 545 and the cam 547 on the guide 548 for the cylinder 504. The downward motion of the cylinder 504 moves the cam 547 to a position below the end of the arm 546 which swings by its own weight so that the mercury switch 544 is tipped and closes the electrical circuit therethrough. The operating solenoid 549 for the valve 522 is the only other piece of apparatus in the circuit including the mercury switch 544.

At the time the positioning of the leads 36 and 39 is taking place, the transfer jaws 424 and 425 are being carried into the central opening 550 in the clamping jaws 500 and 501 and to a position directly over the leads 36 and 39. An adjustment of the valve 459 now occurs and the transfer jaws 424 and 425 are moved downward until the legs 383 of the filament 380 carried thereby are located within the grooved ends of said leads 36 and 39 and the coiled center portion 379 of said filament 380 is at exactly the correct relation to the reflecting surface 41 on the cup 35. 75

The clamping action of the jaws 500 and 501 does not result until the oil pressure in the valve 462 builds up to full delivery pressure after the downward motion of the transfer jaws 424 and 425 stops and results in the flow of oil through pipe 551 to valve 520 and the readjustment of the core 552 thereof. The oil above the piston 513 in the operating cylinder 504 of the clamping device 387 now passes through the passage in the valve core 552 and pipe 553 to the storage tank (not shown) and said cylinder again moves down causing the jaws 500 and 501 to carry the die blocks 537 and 538 into engagement with the leads 36 and 39. The die blocks 537 and 538 are so shaped as to squeeze the grooved ends of the leads 36 and 39 about the legs 383 of the filament 380 therein without changing their general position and pass to one side of the lead 38 and to both sides of the lead 37. The leads 36 and 39 are clamped tightly about the legs 383 of the filament 380 and make excellent electrical and mechanical connections thereto. Angularly bent portions 554 (Fig. 25) of the very ends of the legs 383 of the filament 380 prevent any twisting action thereof or any shock from causing said filament to twist or turn out of position following the withdrawal of the transfer jaws 424 and 425.

The return movement of the transfer jaws 424 and 425 must occur before that of the clamping device 387 and the first operation thereof is the readjustment of valve 443 to allow the air in the bellows 446 to escape through the open port 555 of said valve 443 and the contracting force of the springs 457 to separate jaw 424 from jaw 425. The readjustment of valve 459 and then of valve 485 follows and causes an upward and then a sideward movement of the transfer jaws 424 and 425 bringing them to station X in exactly the reverse order to the earlier movements thereof. During this interval the pipes 460 and 461, valve 462 and pipe 463 function as the means of returning oil from the cylinder 431 instead of conducting oil at pressure thereto and the valve 462 closes because of the lower pressure therein. With the valve 462 closed, the oil holding the core 552 of valve 520 in place drains to the storage tank (not shown) through the pipes 556 and 553 and the spring 557 returns said core 552 to its former position. The clamping device 387 is now returned to its raised position by the readjustment of the valve 514 which causes oil at pressure to flow to the cylinder 504 through the pipe 523, the check valve 525 which opens to the flow of oil in this direction, a portion of pipe 521, the valve 520 and pipe 519. The die blocks 537 and 538 are the first parts of the clamping device 387 to move outward from the leads 36 and 39 and do not disturb said leads 36 and 39 in any way as they are held by the slides 534 and 535 until the separation is effected. The slides 534 and 535 are held in place by the levers 539 and 540 until the jaws 500 and 501 come in contact therewith whereupon both move outward. In the upward movement of the cylinder 504, the cam 547 soon engages the arm 546 which tips the mercury switch 544 so that the electrical circuit to valve 522 is broken and said valve 522 is opened. Oil can now flow through the full length of the pipe 521 and the system is prepared for the next cycle of operation.

Following the operations at station H, the head 40 and cup 35 are indexed to station J, the next in order. The apparatus at this station corresponds to that at station H in that a filament

380 taken from the adjacent turret 376 (Fig. 1) is transferred to mounting relation to the leads 37 and 38 of the cup 35 by the device 386' and the legs 383 thereof are clamped in grooves in said leads 37 and 38 by the device 387'. The transfer device 386' (Fig. 1) is a duplicate of the device 386 at station H and operates in the same manner, except that the filament 380 is taken from a holder 374 on the turret 376 at station Y and is moved to an off-center position in the reflector 41 of the cup 35 at said station J. The clamping device 387', however, differs from the other device in that dissimilarly shaped slides 558 and 559 and die blocks 560 and 561 as shown in Fig. 34 are provided with this device in order to engage leads 37 and 38 instead of leads 36 and 39. Hydraulic operation of the second transfer and clamping devices 386' and 387' respectively is also like that of the other devices 386 and 387 and depends on the adjustment of the control valves 443, 485 and 514 (Fig. 9) which are connected to the operating means thereof. The prior description of the operating means for the first transferring and clamping devices 386 and 387 can be applied to the second operating means because of the duplication of corresponding parts which are given the same numbers with the addition of a prime (see Fig. 9 where, for example, part 431' corresponds to 431, 552' corresponds to 552, etc.). The operation of the apparatus at station J necessarily parallels that at station H and when complete causes all parts thereof to be separated from the parts of the head 40 and the cup 35.

The construction of the hydraulic operating means for each of the different devices except the transfer devices 386 and 386' is very similar in that the oil leakage in each instance is caught and returned to the storage tank by a trough on the operating cylinder in a manner already described in combination with some of them. Each of the transfer devices 386—386', however, have leakage about rod 465 and cylinder 431 which is caught in the trough 562 (Fig. 27) in the latter and is drained through the pipe 563 (Fig. 24) to the arcuate container 564 mounted behind said cylinder 431 on the housing 482. The container 564 is deep enough to surround the end of pipe 563 during the vertical movements of the cylinder 431 and is shaped so as to hold said pipe 563 during the turning movements of the device 386. The leakage about the upper end of the sleeve 479 (Fig. 27) is caught in the trough 565 in the housing 482 and drained through the pipe 566 (Fig. 24) to the flared cup 567 which catches the leakage at the lower end thereof. No leakage is possible between the flared cup 567 and the sleeve 479 as the former turns with and makes a seal with the latter. A spout 568 drains the oil from the flared cup 567 to the trough 569 located on lug 494 of bracket 495 in the range of movement of said spout 568 and pipe connections (not shown) to the trough 569 and container 564 conduct the oil back to the storage tank.

The final operation of the mounting machine in this cycle of operation occurs during the indexing of the head 40 to station K, the unloading station, and is caused by a gradual drop in the track 60 which lowers the holder 50 and the cup 35 away from the positioning ring 73 and locating fingers 79 of the head 40. By this time, the filament mount formed by the filaments 380 and 380 and the leads 36, 37, 39 and 39 is com-

pletely developed and the cup 35 is taken manually from the head 40.

Since each of the different operations of the machine is performed by separately operated hydraulic means and is separately controlled from the indexing means for the turret, failure of any one device to move upward from operative relation to the leads 36, 37, 38 and 39 at the proper time or, in some instances, to operate properly will cause unrelated parts to strike each other, resulting in damage to the machine. For instance, the bending block 198 in the device at station C may become wedged in place and not move at all or not until pressure of the oil in the cylinder has built up. In either case the indexing movement of the turret 56, if allowed to occur at the usual time, would carry the parts of the head 40 against the bending device and the entire machine would be stopped. When any of the devices are not operating correctly they do not return to the upper position at the time the indexing motion is to take place and therefore do not tip a mercury switch mounted in combination with said device. Such mercury switches, are shown in combination with each of the devices at 570 to 579 inclusive in Fig. 9 and are mounted on posts adjacent the operating cylinders of the various devices in a corresponding manner. The mercury switches 571 and 572 in combination with the relocating and bending devices at stations C and D are shown in detail in Figs. 11 and 14 and are tipped by movement of the screw 580 on the respective slides 177 and 221. When either of said slides 177 and 221 is in the up position, the screw 580 engages the arm 581 on one end of a pin (not shown) held by the block 582 and tips the arm 583 holding the mercury switch 571 (or 572) so that it takes the closed position. The block 582 is clamped to the post 209 (or 257) by the block 584 at a definite position and any downward motion of the screw 580 allows the weight of the arms 581 and 583 to turn the support pin (not shown) in the block 582 and tip the mercury switch 571 (or 572) to the open position. The only exceptions to this construction are in the grooving devices 296 and 367 at stations F and G and the transfer devices 386 and 386' adjacent stations H and J. The arm 581 in each grooving device is located over the upper end of one of the rods 301 which is attached to the slide 298 and is tipped by the final movements thereof when said slide 298 reaches its upper limit of movement. The transfer devices 386 and 386' have differently shaped arms 581', in place of the arms 581, which are tipped by engagement with the cylinders 431 or 431' at the upper limit of their movement. The mercury switches 570 to 579 inclusive as shown in Fig. 9 are connected in series with each other and the solenoid 585 of the motor control switch 586 and are normally shunted out of control of the main drive motor 587 of the machine by the cam actuated switch 588. The motor 587 is coupled to the main cam shaft 67 through the belt 589, pulley 590, shaft 591 and the speed reducer gears 592 and 593 and controls all operations of the machine. For the sake of clearness, the gear 593 is shown in Fig. 9 on the end of the shaft 67 opposite to the end on which it is actually mounted, the correct relationship being shown in Fig. 4. When the indexing motion of the turret 56 is about to begin, the mercury switches 570 to 579 inclusive are ordinarily tilted to their closed position by the devices with which they are associ-

ated and the opening of the switch 588 by the cam 594 on shaft 67 has no effect. If one of the devices is not operating correctly, the mercury switch associated therewith will be tilted to the open circuit position and the opening of the switch 588 will break the circuit to the solenoid 585 and cause the motor control switch 586 to open and the motor 587 to stop. The machine cannot therefore be operated when one of the devices is out of order but is again made operative when the situation is corrected.

What I claim as new and desire to secure by Letters Patent of the United States is:

1. Apparatus for making filament mounts for electric incandescent lamps and similar devices comprising a head for holding a portion of the device, a movable carrier for the head, indexing apparatus for advancing the carrier to position the head at each of a plurality of stations in turn, means located at one of said stations for performing one of the mount making operations on the portion of the device held by the head, hydraulic operating means for actuating said first-mentioned means, and means for controlling the hydraulic operating means.

2. Apparatus for making filament mounts for electric incandescent lamps and similar devices comprising a head for holding a portion of the device, a movable carrier for the head, indexing apparatus for advancing the carrier to position the head at each of a plurality of stations in turn, means located at each of a plurality of said stations for performing mount making operations on the portion of the device held by the head, separate hydraulic operating means for actuating each of said first-mentioned means, and means for controlling the hydraulic operating means.

3. Apparatus for making filament mounts for electric incandescent lamps and similar devices comprising a head for holding a portion of the device, a movable carrier for the head, indexing apparatus for advancing the carrier to position the head at each of a plurality of stations in turn, means located at a plurality of said stations for performing mount making operations on the portion of the device held by the head, separate hydraulic operating means for actuating each of said first-mentioned means, and separate means for controlling each of the hydraulic operating means.

4. Apparatus for making filament mounts for electric incandescent lamps and similar devices comprising a head for holding a portion of the device, a movable carrier for the head, indexing apparatus for advancing the carrier to position the head at each of a plurality of stations in turn, means located at one of said stations stations adjacent the path of movement of the head for performing a mount making operation on the portion of the device therein comprising a tool and hydraulic operating means for carrying said tool to and from operative relation to said portion of said device, and means for controlling the hydraulic operating means.

5. Apparatus for making filament mounts for electric incandescent lamps and similar devices comprising a head for holding a portion of the device, a movable carrier for the head, indexing apparatus for advancing the carrier to position the head at each of a plurality of stations in turn, means located at one of said stations adjacent the path of movement of the head for performing a mount making operation on the portion of the device therein comprising a movable

5 tool and hydraulic operating means for carrying said tool to and from operative relation to said portion of said device and actuating said tool therat, and means for controlling the hydraulic operating means.

6. Apparatus for making filament mounts for electric incandescent lamps and similar devices comprising a head for holding a portion of the device, a movable carrier for the head, indexing apparatus for advancing the carrier to position the head at each of a plurality of stations in turn, means located at one of said stations for performing one of the mount making operations on the portion of the device held by the head comprising a movable tool, a vertically disposed cylinder connected to said tool, a piston within said cylinder and a stationary rod connected to said piston and extending through one end of said cylinder for causing said cylinder to be moved and said tool to be actuated when a fluid under pressure is introduced into the said cylinder either above or below said piston, and means for controlling the introduction of the operating fluid into the cylinder.

7. Apparatus for making filament mounts for electric incandescent lamps and similar devices comprising a head for holding a portion of the device, a movable carrier for the head, indexing apparatus for advancing the carrier to position the head at each of a plurality of stations in turn, means located at one of said stations for performing one of the mount making operations on the portion of the device held by the head comprising a movable tool, a vertically disposed cylinder connected to said tool, a piston within said cylinder and a stationary rod connected to the top of said piston and extending through the upper end of said cylinder for causing said cylinder to be moved and said tool to be actuated when a fluid under pressure is introduced into the said cylinder either above or below said piston and means on the upper end of the cylinder for catching the leakage of the operating fluid about the rod and conducting it away therefrom, and means for controlling the introduction of the operating fluid into the cylinder.

8. Apparatus for making filament mounts for electric incandescent lamps and similar devices comprising a head for holding a portion of the device, a movable carrier for the head, indexing apparatus for advancing the carrier to position the head at each of a plurality of stations in turn, means located at one of said stations for performing one of the mount making operations on the portion of the device held by the head comprising a tool, means having slide ways therein for carrying said tool to and from operative relation to said portion of the lamp or similar device, operative means for the tool located in the ways of said last-mentioned means, means for keeping the operative means normally at one position in said ways, and hydraulic operating means connected to said operative means for moving said operative means and said first-mentioned means to carry the tool to and from operative relation to said portion of said device and shift the said operative means in said ways to actuate said tool, and means for controlling the hydraulic operating means.

9. Apparatus for making filament mounts for electric incandescent lamps and similar devices comprising a head for holding a portion of the device, a movable carrier for the head, indexing apparatus for advancing the carrier to position the head at each of a plurality of stations in

turn, means located at one of said stations for performing one of the mount making operations on the portion of the device held by the head, hydraulic operating means for actuating said first-mentioned means, means for controlling the hydraulic operating means to cause it to operate in proper time relation to the indexing movement of the head, and means engaging said first-mentioned means for stopping the indexing apparatus if said first-mentioned means is not at its rest position at the time of indexing.

10. Apparatus for making filament mounts for electric incandescent lamps and similar devices comprising a head for holding a portion of the device, a movable carrier for the head, indexing apparatus for advancing the carrier to position the head at each of a plurality of stations in turn, means located at a plurality of said stations for performing mount making operations on the portion of the device held by the head, separate hydraulic operating means for actuating each of said first-mentioned means, means for controlling the hydraulic operating means to cause it to operate in proper time relation to the indexing movement of the head, and means engaging each of said first-mentioned means for stopping the indexing apparatus if any one of said first-mentioned means is not at its rest position at the time of index.

11. Apparatus for making filament mounts for electric incandescent lamps and similar devices comprising a head for holding and positioning a vitreous portion of the device having metal leads extending therefrom, a movable carrier for the head, indexing apparatus for advancing the carrier to position the head at each of a plurality of stations in turn, mechanism located at one of said stations for bending and repositioning respective leads, hydraulic operating means for actuating said mechanism and means for controlling the hydraulic operating means.

12. Apparatus for making filament mounts for electric incandescent lamps and similar devices comprising a head for holding and positioning a vitreous portion of the device having a metal lead extending therefrom, a movable carrier for the head, indexing apparatus for advancing the carrier to position the head at each of a plurality of stations in turn, mechanism located at one of said stations for bending and repositioning said lead comprising a wedge movable in a path to one side and intersecting the plane of the lead, means for causing said wedge to move along said path until its diverging sides cause it to contact said lead irrespective of any variation in the position thereof, and means for bending the end of said lead over the wedge, and means for actuating the said mechanism in proper time relation to the movements of the carrier.

13. Apparatus for making filament mounts for electric incandescent lamps and similar devices comprising a head for holding and positioning a vitreous portion of the device having metal leads extending therefrom, a movable carrier for the head, indexing apparatus for advancing the carrier to position the head at each of a plurality of stations in turn, mechanism located at one of said stations for bending a pair of said leads which are spaced from each other comprising a floating wedge movable in a path between and intersecting the common plane of both leads, means for causing said wedge to move along said path until its diverging sides cause it to engage one of said leads and, after any necessary side-

ward motion, the other of said leads, and means for bending the ends of the pair of leads over the wedge, and means for actuating the said mechanism in proper time relation to the movements of the carrier.

14. Apparatus for making filament mounts for electric incandescent lamps and similar devices comprising a head with means for positioning a vitreous portion of the device having a metal lead extending therefrom and a movable holder for supporting and keeping said vitreous portion of said device against the positioning means, a movable carrier for the head, indexing apparatus for advancing the carrier to position the head at each of a plurality of stations in turn, means located at a plurality of said stations for performing mount making operations on the lead, means located at at least one of said stations for urging the holder of the head toward the positioning means thereof to force the vitreous portion of the device tightly thereagainst and for locking said holder in place to keep the lead in position during operation of said first-mentioned means, hydraulic operating means for actuating said first-mentioned means, and means for controlling the hydraulic operating means.

15. Apparatus for making filament mounts for electric incandescent lamps and similar devices comprising a head for holding and positioning a vitreous portion of the device having a metal lead extending therefrom, a movable carrier for the head, indexing apparatus for advancing the carrier to position the head at each of a plurality of stations in turn, mechanisms located at respective stations for bending the lead to a predetermined position, for trimming said lead to length and for shaping the end of said lead to receive an end of a filament, separate hydraulic operating means for actuating each of said mechanisms, and means for controlling the hydraulic operating means.

16. Apparatus for making filament mounts for electric incandescent lamps and similar devices comprising a head for holding and positioning a vitreous portion of the lamp device having a metal lead extending therefrom, a movable carrier for the head, indexing apparatus for advancing the carrier to position the head at each of a plurality of stations in turn, means located at one of said stations for reshaping the end of the lead comprising a co-acting die and punch, means for moving said die and punch to and from engagement with said end of said lead and for causing said punch to swage said end, and means for controlling the last-mentioned means.

17. Apparatus for making filament mounts for electric incandescent lamps and similar devices comprising a head for holding and positioning a vitreous portion of the device having metal leads extending therefrom, a movable carrier for the head, indexing apparatus for advancing the carrier to position the head at each of a plurality of stations in turn, means located at one of said stations for displacing portions of one end of the leads to reshape and form grooves therein, means located adjacent a second station for bringing a filament into mounting relation to said leads and the end portions of said filament into the grooves therein, clamping means located at said last-mentioned station for squeezing the grooved portions of the leads about the ends of said filament to fasten said filament securely thereto, and operating means for actuating each of said means in proper time relation to the indexing movements of the carrier.

18. Apparatus for making filament mounts for electric incandescent lamps and similar devices comprising a head for holding and positioning a vitreous portion of the lamp device having metal leads extending therefrom, a movable carrier for the head, indexing apparatus for advancing the carrier to position the head at each of a plurality of stations in turn, means located at one of said stations for displacing portions of one end of the leads to reshape and form grooves therein, means located adjacent a second station for bringing a filament into mounting relation to said leads and the end portions of said filament into the grooves therein, clamping means located at said last-mentioned station for squeezing the grooved portions of the leads about the ends of said filament to fasten said filament securely thereto, separate hydraulic operating means for actuating each of said means, and means for controlling the hydraulic operating means.

19. In a machine of the class described, the combination of apparatus for mounting a filament on a pair of metal leads comprising a movable carrier, a plurality of holders mounted on the carrier shaped to support and accurately position single filaments placed on each, means for moving the carrier to advance the holders from a loading to an unloading station in turn, transfer mechanism for carrying the filament from the holder at the unloading station to mounting relation to the leads, means for attaching said filament to said leads, and means for operating the transfer mechanism and the respective means of said apparatus in proper time relation to each other.

20. In a machine of the class described, the combination of apparatus for mounting a filament having a coiled center portion and parallel end portions extending substantially perpendicular therefrom on a pair of metal leads comprising a movable carrier, a plurality of holders mounted on the carrier, each having a portion for supporting and positioning the coiled center portion of said filament and portions at opposite sides thereof for confining and positioning the end portions of the said filament, means for moving the carrier to advance the holders from a loading to an unloading station in turn, transfer mechanism for carrying the filament from the holder at the unloading station to mounting relation to the leads, means for attaching said filament to said leads, and means for operating the transfer mechanism and the carrier moving means of said apparatus in proper time relation to each other.

21. In a machine of the class described, the combination of apparatus for mounting a filament on a pair of metal leads comprising a movable carrier, a plurality of holders mounted on the carrier shaped to support and accurately position single filaments placed on each, means for moving the carrier to advance the holders from a loading to an unloading station in turn, transfer mechanism for carrying the filament from the holder at the unloading station to mounting relation to the leads, means attached to the transfer mechanism engaging the carrier at the loading station for locating said mechanism with respect to the holder and filament, means engaged by the locating means of the transfer mechanism for positioning said mechanism at the unloading station, means for attaching said filament to said leads, and means for operating the transfer mechanism and the carrier moving means of said

apparatus in proper time relation to each other.

22. In a machine of the class described, transfer mechanism for moving a filament from a loading station to proper relation to a pair of metal leads at a mounting station comprising a pair of jaws for gripping said filament, hydraulic operating means for moving said jaws to and from positions above the loading and mounting stations, other hydraulic operating means for moving the jaws into engagement with the filament at the loading station and to proper relation to the leads at the mounting station and means for causing the different parts of the transfer mechanism to operate in proper sequence.

23. In a machine of the class described, the combination of apparatus for mounting a filament on metal leads extending from a portion of an electrical device in predetermined accurate relation to a reflecting surface on said portion comprising a head having means for positioning said reflecting surface and said portion of said device and a movable holder for keeping said portions of said device against the positioning means and permitting insertion and removal thereof, and means at a predetermined relation to said head for mounting the filament on said leads at the desired relation to the reflecting surface.

24. In a machine of the class described, the combination of means for supporting a reflector portion portion of an electric lamp carrying lead wires, means for accurately determining the location of the focus of said reflector portion, means for affording a relative adjustment between said supporting means and said focus locating means to bring the focus of the reflector portion into registry with said focus locating means, means for supporting a filament, means for bringing said filament and said reflector portion into a definite registry predetermined by the focus locating means so that said filament is located at said focus, and means for securing said filament to said lead wires.

25. In a machine of the class described, the combination of a movable carrier, a head on said carrier, adjustable support means on said head for holding a reflector portion of an electric lamp carrying lead wires, means for accurately positioning said head at each of a plurality of stations into which it is carried by said carrier, focus locator means mounted at one of said stations in a definite predetermined position, means for adjusting said support means to so locate the said reflector portion that its focus bears an exact predetermined relationship to said focus locator means, means at a succeeding station for holding a filament in a definite predetermined position which bears the same relationship to said support means and the reflector portion therein as does the said focus locator means, and means for securing said filament to the said lead wires.

26. In a machine of the class described, the combination of a movable carrier, a head on said carrier, adjustable support means on said head for holding a reflector portion of an electric lamp carrying lead wires, means for accurately positioning said head at each of a plurality of stations into which it is carried by said carrier, focus locator means mounted at one of said stations in a definite predetermined position, means for adjusting said support means to so locate the said reflector portion that its focus bears an exact predetermined relationship to said focus locator means, means located at a succeeding sta-

tion and bearing an exact predetermined relationship to said support means for reshaping and positioning the said lead wires, means at another succeeding station for holding a filament in a definite predetermined position which bears the same relationship to said support means and the reflector portion therein as does the said focus locator means, and means for securing said filament to the said lead wires.

27. In a machine of the class described, the combination of a movable carrier, a head on said carrier, adjustable support means on said head for holding a reflector portion of an electric lamp carrying lead wires, means for accurately positioning said head at each of a plurality of stations into which it is carried by said carrier, focus finding mechanism at one of said stations com-

5 prising means for directing a beam of parallel light rays into said reflector and a focus locator member mounted in a definite predetermined position, said focus locator being capable of providing an indication when it is located at the focus of the said reflector portion, means for adjusting said support means to so locate the said reflector portion that its focus bears an exact predetermined relationship to said focus locator member, means at a succeeding station for holding 10 a filament in a definite predetermined position which bears the same relationship to said support means and the reflector portion therein as does the said focus locator member, and means 15 for securing said filament to the said lead wires.

JOHN FLAWS, JR.

CERTIFICATE OF CORRECTION.

Patent No. 2,297,950.

October 6, 1942.

JOHN FLAWS, JR.

It is hereby certified that error appears in the printed specification of the above numbered patent requiring correction as follows: Page 14, first column, lines 25, 38, 51 and 65, and second column, lines 5, 24, 46 and 69, claims 1 to 8 inclusive, page 15, first column, line 41, and second column, lines 26, 41 and 55, claims 11, 14, 15 and 16 respectively, and page 16, first column, line 21, claim 18, strike out the period at the end of the claims and add the following -

--to cause it to operate in proper time relation to the indexing movement of the head.--;

page 15, second column, line 45, claim 16, and page 16, first column, line 4, claim 18, strike out "lamp"; and that the said Letters Patent should be read with this correction therein that the same may conform to the record of the case in the Patent Office.

Signed and sealed this 29th day of December, A. D. 1942.

Henry Van Arsdale,
Acting Commissioner of Patents.

(Seal)
